DOUBLE PINWHEEL TOY

Paul Millard Lewis, Chicago, Ill.

Application May 14, 1957, Serial No. 46,152

Term of patent 7 years

(Cl. D34—15)

Fig. 1 is a fragmentary front elevational view of a double pinwheel toy, showing my new design;

Fig. 2 is a side elevational view; and

Fig. 3 is a fragmentary rear elevational view thereof.

A portion of the stick has been omitted in Figs. 1 and 3 for convenience in illustration.

I claim:

The ornamental design for a double pinwheel toy, as shown and described.
